UNITED STATES PATENT OFFICE.

FRANK E. CASE, OF CANTON, OHIO.

DESIGN FOR A DENTAL-INSTRUMENT CABINET.

SPECIFICATION forming part of Design No. 35,776, dated February 25, 1902.

Application filed December 21, 1901. Serial No. 86,863. Term of patent 14 years.

To all whom it may concern:

Be it known that I, FRANK E. CASE, a citizen of the United States, residing at Canton, in the county of Stark and State of Ohio, have 5 invented and produced a new and original Design for Dental-Instrument Cabinets, of which the following is a specification, reference being had to the accompanying drawing, forming part thereof.

- The figure is a perspective view of a dental-instrument cabinet, showing my new design.
- As one faces the cabinet the front of the body 1 appears rectangular in form and is 15 divided by the vertical post 2 and the horizontal rib 3 into four sections of nearly equal height, the left divisions being a little narrower than the right ones. The lower left section 4 is finished as a tier of drawers, and 20 the upper left section 5 as a single door. The lower right section 6 is finished as a drawer in the lower part and as a roll-front in the upper part, and the upper right section 7 as an inclined lid in the lower part, 25 above which is the alcove 8, the recessed face of which is finished as a roll-front. The alcove 8 is partly closed on the left by the circular scroll 9 and at the side by the fancy bracket 10, and it is roofed over by the top plate 11 30 of the cabinet, which is supported at its free corner by the turned post 12. The back 13 extends upward from the body 1 and has the variably-curved outline shown, with a hori-

zontal panel-mirror 14 in its lower part. On either side above the mirror are the shelves 35 15, the inner ends of which curve upward and the outer ends downward. The shelves 15 are respectively supported at the outer free corners by the turned posts 16 and at about the middle by the turned posts 17. 40

The side 18 of the cabinet is finished in the various panels shown.

The characteristic feature of my design is the ornamentation on the face of the cabinet, consisting in the series of horizontal panels 45 in the lower left section, the single vertical panel in the upper left section, the single horizontal panel below and the series of rounded horizontal corrugations above in the lower right section, and the inclined horizontal 50 panel below, the circular scroll on the left and the recessed rounded horizontal corrugations above in the upper right section.

Having described my invention, what I claim as new, and desire to secure by Letters 55 Patent, is—

The design for a dental-instrument cabinet, as herein shown and described.

In testimony whereof I have signed my name to this specification in the presence of 60 two subscribing witnesses.

FRANK E. CASE.
